DESIGN FOR A BUCKLE

Charles Rosenblum, Brooklyn, N. Y.

Application July 3, 1935, Serial No. 57,514

Term of patent 3½ years

To all whom it may concern:

Be it known that I, Charles Rosenblum, residing in the Borough of Brooklyn, in the county of Kings and State of New York, have invented a new, original, and ornamental Design for a Buckle, of which the following is a specification, reference being had to the accompanying drawing, forming part thereof.

Figure 1 is a front view, Figure 2 is a top view, and Figure 3 is a side view of a buckle, showing my new design.

I claim:

The ornamental design for a buckle, as shown.

CHARLES ROSENBLUM.
